FISH STRINGER OR SIMILAR ARTICLE

Dixon R. Hoog, 1012 S. Clayton St.,
Bloomington, Ill. 61701

Filed Oct. 8, 1971, Ser. No. 187,940

Term of patent 14 years

Int. Cl. D22—05

U.S. Cl. D22—24

FIG. 1

FIG. 2

FIG. 4

FIG. 3

FIG. 1 is a front elevational view of the fish stringer or similar article showing my new design;

FIG. 2 is a right side elevational view of the fish stringer or similar article illustrated in FIG. 1;

FIG. 3 is a left side elevational view of the fish stringer or similar article illustrated in FIG. 1; and

FIG. 4 is a rear elevational view of the fish stringer or similar article illustrated in FIG. 1.

I claim:

The ornamental design for a fish stringer or similar article, substantially as shown.
